EXTENSION TABLE CONSTRUCTION

Richard Kamholtz, New York, N. Y.

Application March 13, 1947, Serial No. 734,350

6 Claims. (Cl. 311—52)

1

The present invention relates to a table construction, and particularly to a construction for a table which may be used as an occasional table or as a table for utilitarian use, as, for example, a dining table. More particularly still, the invention comprehends a table of the type commonly known as Pembroke and in which a leaf or like element is arranged at right angles to the table top and ordinarily is positioned against a side wall of a room, the table being convertible to one in which the normally upstanding leaf is arranged in the same plane with the horizontal leaf, either with or without an interposed additional leaf to form a table having a large surface and which may be utilized for dining or other utilitarian purposes.

It is an object of the invention to provide an occasional table which may be easily and readily converted to a table for utilitarian use, having a much larger working surface than when in use as a decorative piece of furniture.

It is another object of the invention to provide such a table in which the conversion from one form to the other may be very simply and readily accomplished.

It is a further object of the invention to provide a table of the class previously mentioned in which an additional leaf may be inserted in order to further enlarge the table.

It is a still further object of the invention to provide such a table which is simple in construction and which may be readily and economically manufactured.

Other objects and features of the invention will appear when the following description is considered in connection with the annexed drawings, in which—

Fig. 1 is a perspective view of the table of the present invention arranged to simulate a Pembroke table;

Fig. 2 is a similar perspective view showing the table in its second form and having a much enlarged surface area; in Fig. 2 the two table leaves are shown separated in order to indicate that a separate leaf may be inserted to further enlarge the surface area;

Fig. 3 is a fragmentary perspective view of a portion of the bottom of the table showing the means by which the horizontal leaf of the table may be rotated when converting the table from the form of Fig. 1 to that of Fig. 2, or vice versa;

Fig. 4 is a perspective view of the table framework and supporting legs illustrating the mode in which the leaves are held in position;

2

Fig. 4 is a bottom plan view of the table when arranged as in Fig. 1;

Fig. 6 is a view similar to Fig. 5 but showing the horizontal table leaf during rotation from the position of Figs. 1 and 5 to the position of Fig. 2;

Fig. 7 is a fragmentary, enlarged, bottom plan view of a portion of the table showing particularly the mode of limiting the sliding movement of the horizontal leaf when converting the table to the form illustrated in Figs. 2 and 5;

Fig. 8 is a bottom plan view of the table structure when arranged in the form illustrated in Fig. 2;

Fig. 9 is an enlarged vertical cross-sectional view of the table when arranged as in Figs. 1 and 5, the section being taken on the plane of the line 9—9 of Fig. 5; and

Fig. 10 is a fragmentary cross-sectional view of the upright leaf of the table of Fig. 1 showing particularly the mode for adapting this leaf for support upon the frame-work; this view is taken on the plane of the line 10—10 of Fig. 9.

Referring now to the drawings, the table as shown in Fig. 1 is arranged to have a horizontal surface or leaf 10 and a vertical surface or leaf 11. In this form the table is adapted to serve as a Pembroke table, and the leaf 11 may and ordinarily would be against a side wall. As will be clearly indicated as the description proceeds, the leaf 11 may be moved from its vertical position and after rotating the leaf 10 about a vertical axis and relocating it with respect to the frame-work 12 and legs 13, the leaf 11 may be supported upon the framework in a horizontal position, as shown in Fig. 2. As thus arranged, the parts form a table having a large surface area and, in addition, a separate leaf may be provided and may be inserted between the leaves 10 and 11 for further enlargement of the surface area of the table.

Referring now to Fig. 4, it will be seen that the framework 12 comprises the inner rails 14 and outer rails 15. The legs 13 are formed with flattened extensions 19 (Fig. 7) which extend between the inner and outer rails and are held in position by means of the cross braces 16, which braces terminate in shouldered dowel like portions 29 which pass through holes in the inner rails 14 corresponding to holes in the upper extensions of legs 13 and into blind holes in the outer rails 15. These dowel like portions are then held in place by means of the pins or nails 30. The inner edges of rails 14 are provided with grooves 17, which grooves extend from the left, as seen in Fig. 4, and terminate immediately adjacent the right-hand ends of the rails 14.

Fixed to the undersurface of the leaf 10 are the two members 18 and 20. Member 18 is arcuate in form and extends through substantially ninety degrees. This member is provided with a tongue 21 at its outer surface which cooperates with the groove 17 in the forward rail 14. Member 20 is straight, as seen in Fig. 6, and extends from the outermost end of member 18 rearwardly. This member is provided at its outer surface with a tongue 22 which cooperates with the groove 17 in the rear rail 14.

As will be seen particularly by reference to Figs. 5 and 6, the leaf 10 may be rotated about a vertical axis pivoting upon the rearward corner of the member 20 and being guided by the arcuate form of the member 18, by which means the leaf may be shifted from the position in which it is shown in Fig. 5 to that shown in Fig. 6 in full lines and then, by additional rotation, to a position in which the leaf 10 is at right angles to the framework 12. Subsequently thereto the leaf may be moved outwardly to the dotted line position of Fig. 6, the tongue 22 of member 20 and the then forward corner of the arcuate member 18 then serving to guide the leaf in its sliding movement. The sliding movement just described is limited, due to the fact that the groove 17 in the forward rail 14 terminates adjacent its right-hand end at the point 23 of Fig. 7. Thus, at this point the arcuate member 18 strikes the groove termination indicated at 23 and prevents any further movement.

Also a peg 31 (Figure 5) is inserted in the underside of the leaf 10 to act as a stop and prevent movement of leaf 10 out of register with leaf 11 when the leaves are in the arrangement shown particularly in Figure 1.

The leaf 11 is provided with dowel pins 24, as seen in Fig. 9, which dowel pins extend into the upper flattened portions of the table legs 13, the leaf at this time being between the rear rails 14 and 15. Leaf 11 is provided with the tongued members 25 and 26, which members cooperate with the grooves 17 of the front and rear rails 14 and guide the leaf 11 when it is inserted in the horizontal position to form the table structure of Fig. 2. Further, leaf 10 is provided with holes 27 into which the dowel pins 24 fit when the two leaves 10 and 11 are pushed together to form a continuous table top, as illustrated in Fig. 8. In the usual manner a separate leaf may be provided having dowel holes in one edge and dowel pins in the other and may be inserted between the leaves 10 and 11 to still further enlarge the table top.

It will be seen that by my improved construction I have provided a table which may be readily converted from that form illustrated in Fig. 1 to that of Fig. 2 and have accomplished this result without utilizing any complicated mechanical means and in a manner in which it is very easy to convert the table from one of the forms to the other.

The foregoing description has been given for the purpose of illustrating a preferred form of my invention. It is to be understood, however, that modifications of the structure may be made without departing from the spirit of the invention and, consequently, I wish to be limited not by the foregoing description, which was given solely for purposes of illustration, but, on the other hand, only by the appended claims.

What is claimed is:

1. In a table, in combination, a framework comprising a pair of grooved side rails, a table top

mounted on said framework, and means providing for rotational and translatory movement of said top with respect to said frame, said means comprising a tongued member having the shape of a 90° circle arc mounted on the underside of said table top and extending from one edge of the top towards the center said arc having a radius substantially equal to the distance between said side rails, a second tongued member extending radially inwardly from the said edge of the table and terminating adjacent the end of said arcuate member said second tongued member also having a tongue across its end, said two tongued members interfitting with the grooves in said side rails.

2. In a convertible table, in combination, a framework comprising an inner pair of grooved side rails, said rails being spaced apart, an outer pair of side rails spaced respectively from said inner rails, a plurality of legs, said legs being provided with flattened portions at the upper ends thereof, said flattened portions being inserted between respective ones of said inner and outer side rails, a table top mounted on said framework, a tongued member of arcuate shape extending over substantially a 90° arc of a radius substantially equal to the distance between said inner side rails, and a straight tongued member extending radially of the arc of said arcuate member at one end thereof and perpendicular to the long dimension of said table top, the tongues of said two tongued members interfitting with the grooves in said side rail to provide for pivotal and sliding movement of said table top with respect to said side rails.

3. In a convertible table, in combination, a framework comprising an inner pair of grooved side rails, said rails being spaced apart, an outer pair of side rails spaced respectively from said inner rails, a plurality of legs, said legs being provided with flattened portions at the upper ends thereof, said flattened portions being inserted between respective ones of said inner and outer side rails, a table top mounted on said framework, a tongued member of arcuate shape extending over substantially a 90° arc fixed to the underside of said table top, and a straight tongued member extending radially of the arc of said arcuate member at one end thereof, the tongues of said two tongued members interfitting with the grooves in said side rails to provide for pivotal and sliding movement of said table top with respect to said side rails, the groove in the side rail with which said arcuate tongued piece cooperates terminating adjacent one end of said side rail and acting as a stop to limit the sliding movement of said table top with respect to said framework.

4. In a convertible table, in combination, a framework comprising an inner pair of grooved side rails, said rails being spaced apart, an outer pair of side rails spaced respectively from said inner rails, a plurality of legs, said legs being provided with flattened portions at the upper ends thereof, said flattened portions being inserted between respective ones of said inner and outer side rails, a table top mounted on said framework, a tongued member of arcuate shape extending over substantially a 90° arc fixed to the underside of said table top, and a straight tongued member extending radially of the arc of said arcuate member at one end thereof, the tongues of said two tongued members interfitting with the grooves in said side rail to provide for pivotal and sliding movement of said table top with respect to said side rails, a leaf normally extending between the inner and outer rails of said frame-

work and positioned perpendicularly to the plane of the table top adjacent one edge thereof, means for fastening said leaf to the upper ends of the legs, the pair of spaced apart tongue members fixed to said leaf, the tongues of said last mentioned members interfitting with the grooves in the side rails when said leaf is moved from its position to a position on said side rail adjacent to the table top.

5. In a convertible table, in combination, a framework comprising an inner pair of grooved side rails, said rails being spaced apart, an outer pair of side rails spaced respectively from said inner rails, a plurality of legs, said legs being provided with flattened portions at the upper ends thereof, said flattened portions being inserted between respective ones of said inner and outer side rails, shouldered dowel rods extending between said spaced inner side rails and through said legs and into said outer side rails, a table top mounted on said framework, a tongued member having the shape of a substantially 90° circle arc fixed to the underside of said table top, a straight tongued member extending radially of said arcuate member and adjoining said arcuate member adjacent one edge thereof, said straight member being normally perpendicular to one edge of the table top, the tongues of said two tongued members fitting into the grooves of said inner side rails and serving to provide means for pivoting the said table top with respect to the framework and for sliding said top with respect to the framework, a leaf normally positioned perpendicularly to said table top adjacent one edge thereof, said leaf extending into the space between respective inner and outer side rails, dowel pins in the lower edge of said leaf, said dowel pins extending into cooperating holes in the upper surface of a pair of legs and tongued members fixed to the rear surface of said leaf and spaced apart to extend into the grooves in said inner side rails, whereby when the table top has been pivoted through a 90° arc

and moved towards one edge of the framework the leaf may be placed adjacent the table top with the tongued members thereof in engagement with the grooves in the side rails and the dowel pins of said leaf positioned within holes in the adjacent table top edge to form a continuous extended working surface.

6. In a table, in combination, a supporting framework comprising a pair of spaced side rails each provided with an inwardly facing groove, a table top having at least one straight edge mounted on said side rails, an arcuately shaped tongued member mounted on the under side of said table top with one end of said member adjacent said straight edge thereof, said tongued member having tongues projecting from the arcuate portion thereof and from the straight ends thereof, a second tongued member mounted on the rear of said table top extending perpendicularly to the straight edge thereof and radially of the arcuate member, the tongue of said second tongued member being in alignment with one of the end tongues of said first tongued member, said tongues of said first and second members interfitting with the grooves in said side rails providing for translational movement of said table top along said rails and for rotational movement of said top with respect to said rails.

RICHARD KAMHOLTZ.
